CLAIM

The ornamental design for a storage chest or similar article, as shown and described.

DESCRIPTION

FIG. 1 is a top perspective view of the storage chest or similar article showing my new design;

FIG. 2 is a front elevational view thereof;

FIG. 3 is a right side elevational view, the left side view being a mirror image thereof;

FIG. 4 is a rear elevational view thereof;

FIG. 5 is a top plan view thereof; and

FIG. 6 is a bottom plan view thereof.

FIG. 3
